Primary Examiner — Jennifer Rivard*Assistant Examiner* — Jenny lou M Binas(74) *Attorney, Agent, or Firm* — Faegre Drinker Biddle & Reath LLP(57) **CLAIM**

We claim the ornamental design for a filter for a vacuum cleaner, as shown and described.

DESCRIPTION

FIG. 1 is a front perspective view of a filter for a vacuum cleaner showing our new design;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

The broken lines shown in the drawings illustrate portions of a filter for a vacuum cleaner that form no part of the claimed design.

1 Claim, 7 Drawing Sheets(56)
